IMPEDANCE TYPE DISTANCE RELAY

William K. Sonnemann, Roselle Park, N. J., assignor to Westinghouse Electric Corporation, East Pittsburgh, Pa., a corporation of Pennsylvania

Application March 15, 1945, Serial No. 582,884

5 Claims. (Cl. 175—294)

1

My present invention relates to a new kind of adjustable distance-type relay which has advantages in its adaptability for the adjustment of the relay-characteristic, so that its response-circle may be caused to be placed in different predetermined positions on rectangular coordinates of line-resistance and line-reactance.

An object of the invention is to provide a differential relay, having an operating-coil flux-producing means, and a restraint-coil flux-producing means, with exciting-circuit means for exciting one of the flux-producing means in response to line-voltage alone, and with exciting-circuit means for exciting the other flux-producing means in response to both the line-voltage and the line-current, and with means for varying the ratio of the two voltage-responsive force-components to predetermined values greater or less than unity, and with means for varying the magnitude and the phase-angle of the current-response, or for separately varying the in-phase and out-of-phase components of the current-response, or the like.

With the foregoing and other objects in view, my invention consists in the combinations, systems, methods, apparatus, and parts hereinafter described and claimed, and illustrated in the accompanying drawing, wherein

Figure 1 is a diagrammatic view of circuits and apparatus illustrating my invention in a preferred form of embodiment,

Fig. 2 is a circle-diagram which is referred to in the derivation of the formulas, and

Fig. 3 is a circle-diagram which is referred to in an illustration of the method of adjustment of the relay.

In Figure 1, I have illustrated my invention as applied to a differential relay 4 of a type having a balanced beam 5 which is acted upon by a single voltage-type operating-coil 6, and two out-of-phase voltage-type restraint-coils 7 and 8, in which the flux in coil 8 leads that in coil 7 by approximately 90°, through the medium of a serially connected capacitor C₁, so as to produce a substantially non-pulsatory restraint-force, as is well known. The front end, or operating-coil end, of the beam 5 carries a make-contact 11, which closes when the relay responds, and which is utilized to control any desired relaying-circuit 12.

The ratio K, between the effective number of turns of the restraint-coils 7 and 8, and the effective number of turns of the operating coil 6, is controlled by any suitable means, preferably by means of tap-means K on the operating coil 6, because there is only one coil on the operating end of the beam.

According to my present invention, the relay 4 is utilized to protect an alternating-current line 14 by detecting predetermined fault-conditions therein. The line-voltage E, or an equivalent

2

line-derived relaying-voltage, is applied to the relay by means of a potential-transformer 15. The line-current I, or a line-derived relaying-current, is applied to the relay by means of a line-current transformer 16, and a compensator-impedance comprising a mutual reactance or air-gap transformer jM and a resistance R_e, the resistance being shunted by a variable-ratio transformer 17. The primary winding of the variable-ratio transformer 17 is provided with taps K, which are adjustable so as to vary the turn-ratio in magnitude and in sign or current-direction. The primary winding of the mutual reactance is provided with similar taps K₂. Thus, the relay has three taps K, K₁, and K₂, all of which may be suitably marked or calibrated.

The line-current I is supplied to the primary windings having the taps K₁ and K₂.

The portion of the actuating coil 6 which is tapped by the coil-tap K is connected in series with the compensator impedances R_e and jM, and is energized across the secondary winding of the potential transformer 15.

The restraint-winding 7, and the dephased restraint-winding 8 with its serially connected capacitor C₁, are both energized across the secondary winding of the potential transformer 15.

The voltage impressed on the restraining coils 7 and 8 is E, and the restraining force may be taken as E².

The voltage impressed on the operating coil 6 is

$$E - I (K_1 R_e + j K_2 M) \quad (1)$$

where

$I = I \angle (-\theta)$ = the line-current,
 θ = the angle by which the line-voltage E leads the line-current I, and

K₁ and K₂ are the turn-ratios of the compensator-transformers 17 and jM, respectively, these ratios being scalar values, but variable, through zero, to either plus or minus values.

For convenience in calculation, let us use an equivalent compensator-impedance Z_c and an equivalent compensator-angle θ_c as defined by the equations

$$Z_c = Z_c \angle \theta_c = Z_c \cos \theta_c + j Z_c \sin \theta_c = K_1 R_e + j K_2 M \quad (2)$$

$$Z_c = \sqrt{K_1^2 R_e^2 + K_2^2 M^2} \quad (3)$$

$$\theta_c = \tan^{-1} \frac{K_2 M}{K_1 R_e} \quad (4)$$

Substituting $I = I \angle (-\theta)$ and $(K_1 R_e + j K_2 M) = Z_c \angle \theta_c$ in Equation 1, we may write the operating-coil voltage as

$$E - I Z_c \angle (\theta_c - \theta) \quad (5)$$

The operating force may be taken as the square of the operating-coil turns, K², times the square

3

of the operating-coil voltage which is expressed in line (5), yielding

$$K^2 [E^2 + I^2 Z_c^2 - 2EIZ_c \cos(\theta_c - \theta)] \quad (6)$$

The relay will operate when its operating force is greater than its restraining force, or when

$$K^2 [E^2 + I^2 Z_c^2 - 2EIZ_c \cos(\theta_c - \theta)] > E^2 \quad (7)$$

Dividing through by I^2 , and remembering that E/I is the line-impedance $\dot{Z}$, inequality (7) may be rewritten as

$$Z^2 \left(1 - \frac{1}{K^2}\right) + Z_c^2 - 2\dot{Z}Z_c \cos(\theta_c - \theta) > 0 \quad (8)$$

From the response-circle diagram of Fig. 2, applying the cosine-formula to the triangle represented by the line-impedance along the center-angle S_0 , we find that

$$Q_0^2 = Z^2 + Z_0^2 - 2\dot{Z}Z_0 \cos(S_0 - \theta)$$

or

$$Z^2 + (Z_0^2 - Q_0^2) - 2\dot{Z}Z_0 \cos(S_0 - \theta) = 0 \quad (9)$$

At the balance-point of the relay, the inequality-sign in line (8) becomes an equality-sign, and if K is not equal to 1, the equation may be rewritten, for the balance-point,

$$Z^2 + \frac{K^2 Z_c^2}{K^2 - 1} - \frac{2K^2 \dot{Z} Z_c}{K^2 - 1} \cos(\theta_c - \theta) = 0 \quad (10)$$

Equating equal powers of $\dot{Z}$ in equations 9 and 10,

$$S_0 = \theta_c = \tan^{-1} \frac{K^2 M}{K_1 R_c} \quad (11)$$

$$Z_0 = \frac{K^2 Z_c}{K^2 - 1} = \frac{\sqrt{K_1^2 R_c^2 + K_2^2 M^2}}{1 - \frac{1}{K^2}} \quad (12)$$

$$Z_0^2 - Q_0^2 = \frac{K^2 Z_c^2}{K^2 - 1} = Z_0 Z_c = Z_0 \sqrt{K_1^2 R_c^2 + K_2^2 M^2} \quad (13)$$

$$Q_0^2 = Z_0^2 - \frac{K^2 Z_c^2}{K^2 - 1} = \frac{K^4 Z_c^2}{(K^2 - 1)^2} - \frac{K^2 Z_c^2}{K^2 - 1} = \frac{K^2 Z_c^2}{(K^2 - 1)^2} \quad (14)$$

Equations 11, 12 and 14 express the circle-centerline angle S_0 , the center-displacement Z_0 , and the circle-radius Q_0 , in terms of the relay-variable K , K_1 and K_2 .

It is more convenient, however, to start out with the desired circle-constants S_0 , Z_0 and Q_0 , and to calculate the relay-constants. Thus, the equivalent compensator-impedance is found, from Equation 13, to be

$$Z_c = Z_0 - \frac{Q_0^2}{Z_0} = \frac{Z_0^2 - Q_0^2}{Z_0} \quad (15)$$

Equation 12 yields

$$K^2 = \frac{Z_0}{Z_0 - Z_c} \quad (16)$$

Substituting 15 in 16,

$$K = \frac{Z_0}{Q_0} \quad (17)$$

Substituting, in Equation 2, $S_0 = \theta_c$ from equation 11, we find that

$$K_1 = \frac{Z_c}{R_c} \cos S_0 = \frac{Z_0^2 - Q_0^2}{R_c Z_0} \cos S_0 \quad (18)$$

$$K_2 = \frac{Z_c}{M} \sin S_0 = \frac{Z_0^2 - Q_0^2}{M Z_0} \sin S_0 \quad (19)$$

To determine which way the relay responds, whether to impedance-values Z falling inside or outside of the balance-point circle, it is necessary to restore the inequality-sign to Equation 10, and

to note that Equation 10 was derived from inequality 8 by dividing through by

$$\left(1 - \frac{1}{K^2}\right)$$

If this quantity

$$\left(1 - \frac{1}{K^2}\right)$$

is positive, the division does not reverse the inequality-sign, and the relay responds when the line-impedance terminates outside of the response-circle representing the balance-point conditions. The quantity

$$\left(1 - \frac{1}{K^2}\right)$$

is positive when K is greater than 1, and Equation 17 shows that this is so when the circle-center displacement Z_0 is greater than the circle-radius

Q_0 or when the origin 0 of the R and X coordinates falls outside of the circle. If it is desired to have the tripping area (or the relay-response) inside of the circle, instead of outside, it is necessary to put the make-contacts 11 at the opposite end of the beam 5 of the relay, or to replace the make-contacts 11 with back-contacts 21, so that the operating and restraining coils are interchanged.

If the divisor

$$\left(1 - \frac{1}{K^2}\right)$$

is negative, in deriving the balance-point Equation 10 from the inequality (8), the inequality-sign is reversed, showing that the relay responds when the line-impedance vector $\dot{Z}$ terminates inside of the balance-point circle. This divisor

$$\left(1 - \frac{1}{K^2}\right)$$

is negative when K is less than unity, and Equation 17 shows that this condition prevails when the center-offset Z_0 is less than the radius Q_0 , or, in other words, when the characteristic circle of the relay encloses the origin. Thus, a relay having a make-contact 11 at the same end of the beam 5 as the operating-coil 6, as shown in Fig. 1, will have a response-area inside of the circle, as is desirable.

My present relay is not applicable to the object in view, when the response-circle is to pass through the origin, because, when the ratio $K = Z_0/Q_0$ becomes equal to unity the Z^2 term vanishes, in Equation 8, and the relay no longer has a circle-response. However, the circle may be made to approach quite close to the origin.

Thus, I have provided a relay which can be adjusted to have any response-circle in which the ratio $K = Z_0/Q_0$ is not too near unity. The turn-ratio K , of the restraint-coil turns with respect to the operating-coil turns, determines, and is determined by, the ratio of the circle-center displacement Z_0 and the circle-radius Q_0 , as set forth by Equation 17. The absolute value of the equivalent compensator-impedance Z_c , or the magnitude of the current-response iZ_c , may be adjusted to the value $(Z_0^2 - Q_0^2)/Z_0$, as set forth by Equation 15; and the compensator-angle θ_c , or the phase-shift of the current-response iZ_c with respect to the voltage-response E at unity power-factor, is made equal to the center-line angle S_0 , as set forth in Equation 11. Alternatively, the in-phase and out-of-phase components of the current-response may be independently adjusted by varying the transformer-ratios K_1 and K_2 of

my relay to satisfy Equations 18 and 19, the factors R_e and M being relay-constants, the values of which are supplied by the manufacturer.

To show the application of my relay, by way of example, let it be assumed that the relay is to be adjusted to have a response-characteristic as shown in Fig. 3, which is a part of a circle having the constants

$$S_0 = -71.5^\circ = \text{center-line angle}$$

$$Z_0 = 4.04 \text{ ohms} = \text{center-displacement}$$

$$Q_0 = 5 \text{ ohms} = \text{circle-radius}$$

Let it be assumed that the relay-constants are

$$M = 300 \text{ ohms}$$

$$R_e = 300 \text{ ohms}$$

Then Equations 17, 18 and 19 show that the necessary relay-adjustments are

$$K = \frac{4.04}{5} = .808$$

$$K_1 = \frac{16.32 - 25}{300 \times 4.04} \times (.317) =$$

$$(-.00716) \times (.317) = -.00227$$

$$K_2 = \frac{16.32 - 25}{300 \times 4.04} \times (-.947) =$$

$$(-.00716) \times (-.948) = +.00679$$

The minus sign for K_1 means that the taps K_1 must be adjusted so that the current-direction is the reverse of that shown in Fig. 1, from which the equations were derived.

While I have shown my relay in but a single preferred form of embodiment, I wish it to be understood that the invention is susceptible of embodiment in other forms, and I desire that the appended claims may be accorded the broadest interpretation consistent with their language.

I claim as my invention:

1. An adjustable distance-type relay comprising a differential relay, having an operating-coil flux-producing means, a restraint-coil flux-producing means, exciting-circuit means for exciting one of the flux-producing means in response to line-voltage alone, exciting-circuit means for exciting the other flux-producing means in response to both the line-voltage and the line-current, means for varying the ratio of the two voltage-responsive force-components, and means for varying the magnitude and the phase-angle of the current-response.

2. An adjustable distance-type relay comprising a differential relay, having an operating-coil flux-producing means, a restraint-coil flux-producing means, exciting-circuit means for exciting one of the flux-producing means in response

to line-voltage alone, exciting-circuit means for exciting the other flux-producing means in response to both the line-voltage and the line-current, means for varying the effective ampere-turn ratio of the two flux-producing means, and means for varying the magnitude and the phase-angle of the current-response.

3. An adjustable distance-type relay comprising a differential relay, having an operating-coil flux-producing means, a restraint-coil flux-producing means, exciting-circuit means for exciting one of the flux-producing means in response to line-voltage alone, exciting-circuit means for exciting the other flux-producing means in response to both the line-voltage and the line-current, means for varying the ratio of the two voltage-responsive force-components, and means for separately varying the in-phase and out-of-phase components of the current-response.

4. An adjustable distance-type relay comprising a differential relay, having an operating-coil flux-producing means, a restraint-coil flux-producing means, exciting-circuit means for exciting one of the flux-producing means in response to line-voltage alone, exciting-circuit means for exciting the other flux-producing means in response to both the line-voltage and the line-current, means for varying the effective ampere-turn ratio of the two flux-producing means, and means for separately varying the in-phase and out-of-phase components of the current-response.

5. A protective relay for use on an alternating-current line, said relay comprising, in combination, a differential relay, having an operating-coil flux-producing means, a restraint-coil flux-producing means, voltage-responsive exciting-circuit means for exciting one of the flux-producing means in response to line-voltage alone, current-compensated voltage-responsive exciting-circuit means, including, a variable mutual compensator-reactance, for exciting the other flux-producing means in response to both the line-voltage and the line-current, and means for varying the ratio of the effective ampere-turns of the two flux-producing means.
